INVENTOR:

James H. Rand,

By Robert P. Davis & J. D. Dunbar
THE ATTORNEYS.

UNITED STATES PATENT OFFICE.

JAMES H. RAND, OF NORTH TONAWANDA, NEW YORK.

INDEX.

1,324,467.

Specification of Letters Patent. Patented Dec. 9, 1919.

Application filed August 22, 1918. Serial No. 250,962.

To all whom it may concern:

Be it known that I, JAMES H. RAND, citizen of the United States of America, and resident of North Tonawanda, in the county 5 of Niagara and State of New York, have invented new and useful Improvements in Indexes, of which the following is a specification.

This invention relates to indexes of the 10 overlapping, visible index type, and has to do chiefly with novel means for holding the index elements in spaced relation. In the accompanying drawings, illustrating the preferred embodiment of the invention,—

15 Figure 1 is a front view of part of an index containing the invention;

Fig. 2 is a cross section of the index frame;

Fig. 3 is a rear view of one of the index elements;

20 Fig. 4 is a side or edge view of said index element;

Fig. 5 is a rear view of a group or series of the elements interengaged or interlocked; and

25 Fig. 6 is a section on line 6—6 of Fig. 1.

The index frame may be of usual form, and as herein shown comprises the back F of sheet metal having its side margins bent over to form a pair of inturned flanges f, f.

30 Each index element of the series is made of suitable sheet material, and preferably of transparent, flexible, resilient sheet material, such as sheet celluloid. This possesses admirable qualities of both stiffness and re-

35 silieney suited for the requirements of the structure hereinafter described, and also permits the element to be used as a holder for removable insert cards or slips on which the entries may be made, through which

40 transparent holder the inserts may be read without removing them.

Each index element comprises a front leaf 1 and a rear leaf 2 folded over upon the front leaf and forming therewith a pocket 45 adapted to hold an insert card or slip (not shown). The resilience of the material causes the leaves to press lightly together and so to pinch the insert and hold it against accidental dislodgment. The rear leaf 2 is 50 preferably made integral with the front leaf, but it might conceivably be formed in a separate piece and attached to the front leaf. The rear leaf terminates short of the edge of the front leaf and its extremity is 55 rolled or bent over away from the front leaf as shown at 5 to form a lip in a posi-

tion spaced inwardly from the edge of the front leaf adapted to engage the edge of the next adjacent underlying element, thus holding the successive overlapped elements 60 in spaced relation with their margins exposed to display index matter, which may be displayed either on the exposed margin of the index element itself or on the margin of a card insert showing through the transparent leaf of the element. The edge of the front leaf 1 also preferably terminates in a roll or folded lip 6, which affords a handsome finish, stiffens the edge of the element, prevents it from warping, and furnishes an edge which better fits the spacing 65 lip 5 than a straight edge would do.

Each front leaf has a pair of lateral projections 3, adjacent to the edge opposite the fold, extending into the channels of the 70 frame formed by the flanges f. Thus a series of elements are held in the frame by the lateral projections 3, and are mutually spaced and supported by the spacing lips 5.

The free edges of the index elements, that 75 is, the edges not retained in the frame by the projections 3, are provided with lateral projections 4, 4, which rest on the outer face of the frame flanges f, f.

In order that the elements may be sprung 80 or bent to insert the projections 3 under the flanges f of the frame without buckling or distorting the lips 5 and 6, each lip is cut away or severed at about the middle, as shown at 5' and 6' (Fig. 5). 90

I claim:

1. An index having a series of overlapping index elements of transparent, resilient sheet material, each comprising a front leaf and a rear leaf, and spacing means on said 95 rear leaf adapted to engage the edge of the next adjacent underlying element and to hold said elements in spaced relation with their margins exposed.

2. An index having a series of overlapping index elements of sheet material, each comprising a front leaf and a rear leaf, the extremity of the rear leaf having a bent over lip adapted to engage the edge of the next adjacent underlying element and to hold said elements in spaced relation with their margins exposed, said bent over lip being severed to permit the element to be bent without buckling or distorting the lip. 105

3. An index comprising a frame having 110 opposed channels, and a series of overlapping index elements of transparent, resil-

ient, sheet material, each comprising a front leaf having lateral projections extending into said channels, and a rear leaf forming with the front leaf a pocket, said rear leaf being formed integrally with and folded over upon said front leaf and terminating short of the edge of said front leaf, the extremity of the rear leaf being bent over to form a lip adapted to engage the edge of the front leaf of the next adjacent underlying element and to hold said elements in spaced relation with their margins exposed.

4. An index having a series of overlapping index elements of sheet material, each comprising a front leaf having along its extremity a bent over lip, and a rear leaf terminating short of the edge of the front leaf and of said bent over lip, said rear leaf also having at its extremity a bent over lip terminating short of the edge of the index element adapted to engage the lip at the

edge of the front leaf of the next adjacent underlying element, and to hold said elements in spaced relation with their margins exposed.

5. An index having a series of overlapping index elements of sheet material, each comprising a front leaf having along its extremity a bent over lip, and a rear leaf terminating short of the edge of the front leaf and of said bent over lip, said rear leaf also having at its extremity a bent over lip adapted to engage the lip at the edge of the front leaf of the next adjacent underlying element, and to hold said elements in spaced relation with their margins exposed, both of said lips being severed at the middle to permit the element to bend without buckling or distorting the lips.

Signed by me at North Tonawanda, N. Y., 40
this 11th day of August, 1918.

JAMES H. RAND.
